UNITED STATES PATENT OFFICE.

JAMES C. RANKINE, OF PAWTUCKET, RHODE ISLAND, AND GEORGE H. GOLDSMITH, OF BIDDEFORD, MAINE.

ATOMIZER OR HUMIDIFIER.

1,072,031.

Specification of Letters Patent. Patented Sept. 2, 1913.

Application filed September 1, 1910. Serial No. 580,685.

To all whom it may concern:

Be it known that we, JAMES C. RANKINE and GEORGE H. GOLDSMITH, citizens of the United States, residing, respectively, at Pawtucket, in the county of Providence and State of Rhode Island, and Biddeford, county of York, and State of Maine, have invented a new and useful Improvement in Atomizers or Humidifiers, of which the following is a specification.

This invention relates to atomizers or humidifiers, and pertains more particularly to an improvement in that class of devices which are used in large buildings, such as factories or hospitals, for the purpose of dispersing atomized or substantially vaporized water, disinfectants, or other liquids in the atmosphere of the building by causing the moisture to be carried out upon currents of air.

The principal object of our invention is to construct a device of this character which is practically self-contained, and may be carried by brackets attached to the walls or the ceiling of the room or hall in which the apparatus is to be used.

Furthermore, it is intended to provide an atomizer of this type which is capable of dispersing an atomized fluid through a plurality of passages through which currents of air are directed at various angles, thereby causing the complete dispersion of the finely divided particles of the fluid into every portion of the surrounding atmosphere.

Furthermore, in the present apparatus it is intended to combine such improvements in details of construction and assemblage of parts as to render the operative device particularly well adapted to fulfil the purpose of an apparatus of this character.

Referring to the accompanying drawings, which form a part of this specification and in which like numerals indicate like parts throughout, Figure 1 is a vertical sectional view taken centrally through the atomizer, Fig. 2 is a detail view taken on the line 2—2 of Fig. 1, Fig. 3 is a sectional view taken on the line 3—3 of Fig. 1, and Figs. 4, 5 and 6 are detail fragmentary views of the atomizing means.

Referring more particularly to said drawings, 1 indicates a dish-shaped receptacle or casing having its bottom inclined toward the center and merging in a chamber 2.

Said chamber 2 has a central opening 3 to which is attached the reservoir 4. A supply pipe 5 suitably connected to said reservoir and leading from a supply tank 6 is adapted to supply water or other suitable liquid to the atomizer, and is fed through the automatic control of the water in the tank 6. A float valve 7 constitutes the automatic control of the liquid and maintains the latter at the predetermined level which will prevent the overflow of the atomizer and its connected parts.

Supported within the chamber 2 and rigidly spaced from the inner surfaces thereof, is a cup-shaped element 10, said cup-shaped element having inner and outer concentric members 11 and 12. The outer of said members 12 consists of a shell whose upper edges flare outwardly in general conformity to the shape of the casing and whose central portion is upwardly formed or spun as at 13 to provide a socket or bearing for a step bearing 14, whose function will hereinafter appear. The inner concentric member 11 consists of a circularly channeled member spaced from the inner and outer walls of the member 12 and supported upon tubular members 15, rigidly carried by the member 12, and forming conduit members through which water from the chamber 2 and consequently the reservoir 4 may find its way into the interior of the channel formed in member 11. Said step bearing 14 is so constructed as to rest upon the upper edge of the socket formed by the inner wall 13, and has revolvably stepped therein a shaft 16, said shaft 16 extending upwardly into the upper portion of the atomizer, passes through the motor 17, and supports at its upper end the fan 18. Said motor 17 is supported by, and spaced from an intermediate canopy 8. Said intermediate canopy 8 consists of outwardly and downwardly inclined portions 19, whose outer edge is suitably carried by elements later described and secured to the casing 1, and an inwardly and downwardly inclined portion 9 which forms the direct support for said motor 17.

The motor 17 and the fan 18 are inclosed by a canopy 21, said canopy 21 being substantially bell-shaped and having its lower edge spaced on all sides from the canopy 8, and having its top suitably apertured to permit the ingress of air to the fan. The

latter is mounted to throw the drawn-in air downwardly among the several parts of the apparatus and between the canopies and elements as indicated by the arrows, for 5 the purposes hereinafter set forth.

Supporting the lower and outer edge of the portion 19 of the canopy 8, is a flat ring or annulus 22, said annulus being supported by the bolts 20. Interposed between 10 said annulus 22 and said edge of member 19 is a second flat ring or annulus 23, the latter having a limited revoluble movement upon the annulus 22 by reason of the slots 24 through which bolts or rivets 25 loosely 15 pass, as most clearly shown in Fig. 4.

Revolubly mounted upon the lower face of the ring 22, and spaced thereon, throughout the entire circumference of the ring is the plurality of grids or vanes 26 which constitute 20 the means for atomizing the fluid. Said grids or vanes 26 comprise substantially rectangular sheets of metal or other suitable material having projected from their rear edges the wings 27 and having 25 projected at right angles from their upper edges the aperture flanges 28. Said wings 27 are each provided with an upwardly projecting spindle 29. Said grids or vanes 26 are pivotally secured to the ring 30 or annulus 22 by means of rivets or bolts passed through said flanges 28 and said annulus 22, with the wings 27 projecting rearwardly toward the center of said ring. The inner peripheral edge of the annulus 23 35 projects beyond the corresponding edge of the annulus 22, and is provided with radial slots 30 corresponding in number to said vanes. In each slot 30 projects one of the spindles 29, whereby, by movement of said 40 annulus 23, the positions, or angular relation of the vanes 26 with relation to the annulus 22 may be adjusted. A handle 31 secured to the movable annulus 23 renders the 45 adjustment of the vanes a matter of ease and accuracy, whereby the quality or fineness of the atomized liquid may be readily regulated.

Mounted upon the shaft 16, and fixed thereon directly above the bushing or step 50 bearing 14 is a hub 32 carrying a spider 33, said spider forming the center of a disk 34. Said disk 34 consists of a substantially flat portion extending outwardly from said spider toward the middle portions of the 55 vanes 26, and a downwardly extending portion 35 which projects very nearly to the bottom of the channel formed by the inner member 11 above described. Thus, as the disk 34 is revolved with the shaft 16 this 60 portion 35 operates in a body of water, and as the disk assumes a high speed, capillary attraction and centrifugal motion will cause the water to creep up in the inner and outer sides of the downwardly extending portion 65 25 and outwardly over the surfaces of the

disk 34 until it is finally discharged against the vanes 26 to be broken up into a fine spray or atomized. Should the supply of water carried outwardly by the disk become excessive, it will be permitted to drop again 70 into the casing 1 to be again returned to the supply in the chamber 2.

It has been above stated that the air currents set up by the fans 18 are broken up into a plurality of annular streams. This 75 is done to more thoroughly disseminate or disperse the spray and to relieve any vacuum or suctional effect along the surfaces of the disk 34. As indicated by the arrows in Fig. 1, one current of air is set up through the 80 opening between the lower edge of the bell canopy 21 and the ridge formed by the inclined portions of the intermediate canopy 8. This current acts upon the spray or atomized fluid after it has been thrown out 85 from the casing 1 over the edge 36; and tends to throw it at a great distance into the surrounding atmosphere. The currents indicated by the arrows traversing the space on each side of the channeled member 11 90 and issuing outwardly along the top and bottom surfaces of the disk 34, not only aid the outward action of the water toward the vanes 26, but tend to eliminate any vacuum or suctional effects which might be set up 95 were no compensating air supply provided, and also aid the vanes 26 in breaking up, disseminating and distributing the supply to be vaporized.

It is very often desired, where the device 10 is used in cotton mills and similar factories where a great deal of fiber is flying, to clean out the device and to renew the water contained in the reservoir 4 and the chamber 2. For this purpose, a waste box 37 having a 13 downwardly projected spout 38 is mounted suitably adjacent the casing 1 and receives a revoluble elbow or funnel 39 which forms a free terminal of the reservoir 4. When the elbow 39 is projected upwardly, the 11 water, of course, will be retained in the reservoir 4 to its predetermined level, but when the latter is turned downwardly, through the medium of the hand wheel 40, the contents of the reservoir 4 and the chamber 2 will be 11 permitted to rapidly pass away. It will be noted that the upper or free end of the elbow 39 is placed on a level which corresponds to the desired normal level of the fluid in the chamber 2, so that it is impossible for the apparatus to become flooded and to expel its contents over the edge 36 of the casing 1, but, on the other hand, the excess fluid will be caused to flow over the edge of the upturned elbow 39 and permitted 125 to pass away through the waste pipe 38.

The operation of our improved apparatus as above described will be obvious from the foregoing exposition, and its evident advantages readily understood.

While the construction above described indicates our preferred embodiment, we do not desire to be limited in details to the particular elements described.

5 Having thus described our invention, we claim as new and desire to secure by Letters Patent;—

1. In an atomizer, a fan, a fluid supply, means to atomize the fluid, means to support 10 said atomizing means, a horizontal disk for feeding the fluid to the atomizing means, means to direct currents from the fan along the top and bottom faces of the disk, and means to direct a current from the fan 15 against the atomized fluid after its issuance from the atomizing means.

2. An atomizer, comprising, in combination, a fluid supply, means for centrifugally feeding said fluid to an atomizing means, 20 the means for atomizing the fluid, and means to direct a plurality of air currents against said fluid at various stages during its atomizing operation.

3. An atomizer, comprising, in combination, a fluid supply, means for centrifugally feeding said fluid to an atomizing means, the means for atomizing the fluid, means for adjusting the atomizing means to vary the spray, and means to direct a plurality of air 30 currents against said fluid at various stages during its atomizing operation.

4. An atomizer comprising a fluid supply chamber, a secondary circular channeled member immersed in said supply chamber, 35 ring-like revoluble means in said secondary member to centrifugally draw on the supply in said secondary member, an element to which said ring-like means is secured, said element having a central opening, atomizing 40 means at the periphery of said element to receive the fluid, means to direct air currents through said opening of said element against the fluid before the latter is atomized, and means to direct an air current 45 against the atomized fluid.

5. An atomizer, comprising, in combination, a fan, a fluid supply chamber, a centrifugal feeding means formed with a central opening and having an element immersed 50 in said fluid chamber, an atomizing means adjacent said feeding means arranged to receive fluid fed by the latter, and means to direct the currents of air from said fan along the top of the feeding means, and 55 through said opening thereof, and along the bottom of the feeding means.

6. In a device of the type set forth, a fan, a fluid supply chamber, centrifugal feeding means having an element immersed in said

chamber, an annulus, atomizing means consisting of a plurality of vanes surrounding the feeding means and depending from said annulus and disposed so as to receive the fluid from said feeding means, means to pivotally move said vanes to vary the atomizing effect thereof, and means to direct the currents from said fan along the path of the centrifugally fed fluid. 60

7. In an atomizer, atomizing means, an element arranged adjacent said means and 70 having a central inlet, means to supply liquid to said inlet so that same engages on opposite sides of said element, means to supply a current of air to said element, and means to direct the air current so that same 75 passes along the top of said element through the inlet thereof and along the bottom thereof to feed the fluid to said atomizing means.

8. In an atomizer, atomizing means, an element arranged adjacent said means and 80 having a central inlet, means to supply liquid to said inlet, means to supply a current of air and means to direct the air current onto said element at the center thereof to permit the air to assist in forcing the 85 liquid from the center of the element to the atomizing means.

9. In an atomizer, a feed disk, atomizing means disposed adjacent to said disk, means to supply fluid to said disk at the center 90 thereof, means to supply a current of air, and means to direct the air current onto said disk at the center and on opposite sides thereof to feed the fluid to said atomizing means. 95

10. In an atomizer, atomizing means composed of a series of pivoted atomizing elements, an annular member having connection with each of said elements whereby when said member is given partial rotary 100 movement all of said elements will be moved in unison, means to supply fluid to the atomizing means, and means to supply a current of air to said atomizing means.

In testimony whereof we have signed our 105 names in the presence of two subscribing witnesses.
